HAIR WAVING

Alexander L. Wilson, Indiana Township, Allegheny County, and Henri Morin, Mount Lebanon Township, Allegheny County, Pa.; said Wilson assignor to Carbide and Carbon Chemicals Corporation, a corporation of New York

No Drawing. Application June 2, 1937,
Serial No. 145,948

8 Claims. (Cl. 167—87.1)

Compositions for use in those procedures which accomplish the so-called permanent waving of hair and which contain certain organic bases, or amines, of the class of which morpholine is typical, have been disclosed and claimed in copending application Serial No. 145,949, filed June 2, 1937 by A. L. Wilson. The organic bases of the class mentioned are water-soluble, volatile, mildly alkaline compounds which are capable of evaporating while exerting a substantially constant alkaline action on the hair, and their use is highly desirable from many standpoints.

This invention concerns improvements in hair waving compositions in which the softening agents discussed above are combined with various modifying materials. It is a principal object of the invention to provide compositions containing ingredients selected to enable the fullest advantages to be derived from the use of the softening agents described.

The organic bases useful in this invention may be chosen from a group including morpholine and the addition and substitution products of morpholine which are water-soluble and basic in character. These should be selected from the class of such products whose boiling points, or the boiling points of their aqueous solutions, lie between about 80° and 140° C. Representative substances which are satisfactory are 2,6 di-methyl morpholine, N-ethyl morpholine, N-methyl morpholine, N-ethoxy ethyl morpholine, N-vin oxy ethyl morpholine, and related alkyl, alkylene, alkyloxy and alkyleneoxy derivatives of morpholine. Morpholine,

is a mildly alkaline, water-soluble liquid of moderate volatility which is non-hygroscopic, and which has a faintly ammoniacal odor. It boils at 128.3° C., and it has a specific gravity of 1.0016 at 20°/20° C. A 25% aqueous solution of morpholine has a pH of about 11.2, and it can be used in the compositions of this invention in concentrations of from 3% to about 30%.

The substances described exert a very beneficial softening action on hair since the softening composition can be applied in the waving operation without the necessity of strongly alkaline solutions initially and without forming strongly basic residues by evaporation of inert materials.

In forming our improved waving compositions, the action of the softening agent on the hair is controlled and modified through its combination

with such materials as weakly adhesive thickeners, oils or fats, hygroscopic materials, and emulsifying agents. For example, the waving action is facilitated, and increased crispness is secured, by including rosin, gum arabic, gum tragacanth, or the like in the composition. Oils and fatty substances, such as mineral oils, lanolin, olive oil, castor oil and related oleaginous materials, have a beneficial effect on the hair and may be used in various amounts. Glycerol and the alkylene and polyalkylene glycols may be used in suitable small amounts to utilize the softening effect of moisture retained in the hair by their hygroscopicity. Suitable emulsifying agents may be used to form the entire composition into emulsions for convenient application. The emulsifying agents preferred are those resulting from the combination of higher fatty acids or the like with morpholine or the morpholine addition or substitution product used as the hair softening agent. In this case, the organic base of the emulsifier performs two functions, since its alkalinity will be available to at least some extent as the waving operation proceeds.

The following examples of hair waving compositions and procedures will illustrate the invention:

Example 1

The hair to be waved was segregated in tresses and thoroughly wetted with a composition composed of 16% of morpholine and about 1% of light wood rosin dissolved in water. The tresses were then wound tightly on mandrels of the type customary in permanent waving practices, and subjected to heat applied electrically by means of resistance elements. After about 15 minutes, the heating was discontinued, and finally the hair was released from the mandrels.

This operation produced deep, crisp waves which were natural in appearance, and which rendered subsequent hair dressing very easy. The hair retained most of its natural lustre, and was free of harsh, brittle ends which not infrequently appear in waving operations.

Example 2

The hair, prior to the application of a waving liquid as described above, was treated with a composition composed of 74 parts by weight of castor oil, 24 parts by weight light mineral oil, 5 parts by weight of glycerol and 1 part by weight of morpholine, the whole being emulsified with 10 parts by weight of water and 4 parts by weight oleic acid.

This composition served to condition the hair so that the following waving operation proceeded more satisfactorily, and resulted in a desirable lustre and smoothness of the waved hair.

5 A combined waving and treating liquid of desirable characteristics was formed by combining 5 parts of the emulsion just described with 1 part of morpholine and 3 parts of water. This fluid was employed directly as a waving composition.

Example 3

Another composition was prepared from 10.0% of a mixture of castor and olive oils, 1.8% stearic acid, 15.3% morpholine and 72.9% water, all weight. The stearic acid was melted in the oils and 0.9 part by weight of morpholine was stirred in to form a clear solution. To this were then slowly added 10 parts of water which resulted in a thick, creamy emulsion. The balance of the water and morpholine was added to the initial emulsion to give a stable, mobile fluid for use directly as a permanent waving liquid.

Example 4

25 A composition containing both rosin and oils was formed of the following materials:

	Per cent by weight
30 Mixed castor and olive oils	9.9
Stearic acid	1.8
Morpholine	15.2
Light rosin	1.0
Perfume oils	0.8
35 Water	72.0

As in the previous example, the oils were emulsified with the stearic acid, part of the morpholine and some of the water. The rosin was heated with half its weight of morpholine to give a clear solution to which was slowly added the remainder of the morpholine and water. This rosin solution was then stirred into the oil emulsion.

The foregoing compositions are all concerned with morpholine itself as the organic base, but it will be understood that the other substances of the general class shown may be substituted for it on an equivalent weight basis. It will, of course, be clear that various scented materials or 50 medicaments can be included in the compositions of this invention, and that many variations in the specific compositions are possible.

The waving operations using the compositions of this invention follow, in general, the usual 55 practice in this art. It is preferable to apply the waving liquid to the hair after it has been separated into tresses, and before it is wound on mandrels or curlers, but these operations may be carried out in reverse order if desired. Heating periods of 5 to 25 minutes are usually sufficient, and in most cases heat need not be applied for more than about 10 minutes. Electrical resistance elements form the customary heat source, but heat generated chemically or otherwise can also 60 be used. Evaporation of the waving liquid at atmospheric temperatures only is adequate in some cases.

The production of lasting waves by means of the compositions and methods of this invention 70 has been uniformly successful on almost all types of hair. Even in those cases where bleaching or dyeing of the hair precluded successful waving by previously known methods, it was found that the compositions of this invention permitted

satisfactory waving to be carried out. This has also been found to be true in instances where waving by other means had subjected the hair to such drastic treatment as to damage its structure severely. In almost every instance the compositions of this invention have been found to produce waves of adequate depth and desirable crispness. Repeated use of our new fluids has shown that no detectable injury to the hair results, and, in fact, such repeated use has induced a very satisfactory physical condition of the hair.

Modification of numerous features of the compositions and procedures described will be apparent, and such variations are included within the scope of the invention as defined by the appended claims.

We claim:

1. A hair waving preparation which comprises an aqueous solution containing from about 10% to about 20% by weight of morpholine and about 1% by weight of rosin.

2. A hair waving preparation which comprises an aqueous composition essentially containing from about 3% to about 30% of morpholine together with an oil.

3. A hair waving preparation which comprises an aqueous composition essentially containing a morpholine, which composition boils between about 80° and about 140° C., together with an oleaginous material and an emulsifying agent formed by the reaction of a morpholine and a higher fatty acid.

4. A hair waving preparation which comprises an aqueous composition composed of about 9.9% of a mixture of castor and olive oils, about 15.2% morpholine, about 1.0% rosin, about 1.8% stearic acid and about 72% water, the whole being emulsified by means of the reaction product of the stearic acid with part of the morpholine.

5. Method of waving hair which comprises forming the hair into waves and fixing the wave therein by the action of heat and a softening agent comprising an aqueous composition essentially containing a morpholine, which composition boils between about 80° and about 140° C., together with an oleaginous material and an emulsifying agent formed by the reaction of a morpholine and a higher fatty acid.

6. A hair waving preparation which comprises an aqueous composition containing from about 10% to about 20% by weight of a morpholine, said composition boiling between about 80° and about 140° C., and about 10% by weight of oil, the whole being emulsified by means of the reaction product of part of the morpholine with a small amount of a higher fatty acid.

7. A hair waving preparation which comprises an aqueous composition containing from about 10% to about 20% by weight of morpholine, about 10% by weight of oil and about 1% by weight of rosin, the whole being emulsified by means of a small amount of the reaction product of stearic acid and morpholine.

8. A hair waving preparation which comprises an aqueous composition containing from about 10% to about 20% by weight of morpholine, about 10% by weight of oil and about 1% by weight of rosin, the whole being emulsified by means of a small amount of the reaction product of oleic acid and morpholine.

ALEXANDER L. WILSON.
HENRI MORIN.
